UNITED STATES PATENT OFFICE.

THEODORE H. OPPENHEIM AND BERNARD SELHORST, OF COLDWATER, OHIO, AS
SIGNORS TO NEW IDEA SPREADER CO., OF COLDWATER, OHIO, A CORPORATION OF
OHIO.

CORN-HUSKING MACHINE.

Application filed November 29, 1924. Serial No. 753,907.

This invention relates to corn husking machines, and has special reference to the frame structure.

One object of the invention is to provide a frame or support for the several operating parts, which will be compact, strong, rigid and durable and which will produce a comparatively low machine which may be easily moved through the door of a barn or storehouse and will also permit a farmer to use a low wagon and transfer the bundles of corn from such a wagon to the feeding table of the husking machine.

Another object of the invention is to provide an improved support for the blower spout; and another object of the invention is to provide an improved mounting for the ear conveyor.

The invention also seeks to provide a structure whereby the side table may be disposed within the lines of the sides of the machine when the machine is to be transported.

Other objects will appear incidentally in the course of the following description, and the invention resides in certain novel features which will be particularly pointed out in the appended claims.

In the drawings:

Figs. 1 and 2 are elevations, partly broken away, of a corn husking machine embodying our present invention, the views showing opposite sides of the machine and Fig. 1 showing the machine arranged for use, while Fig. 2 shows it arranged for transportation or storage;

Fig. 3 is a plan view of the machine, showing the blast spout and the ear conveyor in the position illustrated in Fig. 2;

Fig. 4 is a rear end elevation.

The machine is mounted for travel upon wheels 1 and 2, the front wheels 1 being mounted upon spindles adapted to turn pivotally on the ends of the front axle and connected by a link 3, whereby the wheels are always parallel. This arrangement will permit the machine to be easily steered around sharp turns. To the front axle 4 we secure a steering pole or draft tongue 5 and we also provide short guide posts 6 depending from the front end of the frame, the rear end of the frame being carried by the rear axle 8 upon which is secured an inverted channel bar 9', whereby the rear axle is reinforced, and a supporting base of appreciable area is

provided for the side bars 9 of the frame. 55 These side bars are preferably angle bars, but they may be of any other preferred configuration. They are secured rigidly to the channel bar 9' and they constitute the chord members of trusses whereby the load 60 imposed upon the frame is carried with minimum strain. Angle bars 10 are secured to the under sides of the side bars and extend between the same so as to impart rigidity thereto and prevent lateral spreading of the 65 frame. The trusses, of which the side bars are lower chords, are defined on one side of the machine by the forward inclined angle bar 11 which constitutes a part of the husking roll bed, the rear inclined bar 12 and intermediate bar 13, the rear bar 12 and the intermediate bar 13 extending to and above the top sill or beam 14 of the frame. On the opposite side of the machine there are the forward inclined bar 15 which constitutes part of the husking roll bed, rear inclined bar 16 and intermediate bar 17, the bars 16 and 17 extending to and above the top sill or beam 18. The lower ends of the inclined bars 11, 12, 15 and 16 are connected 70 rigidly with the respective side bars 9, either by being bolted or riveted directly thereto or being connected therewith through intermediate gusset plates 19'. The rear end of the frame bar 15 is rigidly secured to the bar 16, and the rear end of the bar 11 is rigidly secured to the bar 12. The drawings show the bar 13 extended vertically downward and secured to the subjacent side bar 9 while the bar 17 is connected with the cor- 75 80 85 90 95 100 105

responding side bar 9 by a vertical bar 171. A very strong load-carrying frame is thus produced. The bars 11 and 15 are bolted or riveted to the intermediate bars 13 and 17 and extend past the same to the bars 12 and 16, respectively, to which their ends are rigidly secured. The bars 12 and 16 also define the rear end of the machine and the upper members 14 and 18 are rigidly secured thereto. Vertical bars 19 are provided at the front end of the frame and extend between the respective side bars and top sills, as clearly shown in Figs. 1 and 2. Intermediate the bars 17 and 19 on one side and the bars 13 and 19 on the other side of the machine are vertical members 20 which are rigidly secured at their upper ends to the top side

beams and near their lower ends to horizontal bars 21 which extend rearwardly from the front vertical bars 19. The spaces defined by the several frame bars are closed or covered by suitably shaped sheet metal panels, such as 22, which are rigidly secured by bolts or rivets to the several frame bars, so that the entire interior of the machine will be enclosed and the operator will be protected from possible injury through contact with the moving parts. Such parts of the operating gearing as may be located on the outside of the machine are covered by gear casings 23 of proper form, as will be readily understood. Between the lower ends of the vertical members 20 and the respective inclined bars 11 and 15, short members 24 may be secured so as to firmly support the bars 21 and impart additional rigidity to the frame structure. The upper extremities of the bars 16 and 17 at one side of the machine and of the bars 12 and 13 at the opposite side, respectively, are rigidly secured together to provide a firm support for the upper ends of the snapping rolls, and frame plates 25 are secured upon the upper ends of these bars so as to protect the operator against accidental contact with the rolls or parts adjacent the same. The snapping rolls and the husking rolls, indicated at 26 and 27, respectively, are mounted in cross bars or yokes 28 which are bolted to the frame members 11, 13, 15 and 17, respectively, and extend across the entire width of the machine, so that they in turn constitute bracing or tie members to prevent spreading of the sides of the frame and to maintain the same in proper plumb condition at all times. The arrangement of the frame elements 11, 13 and 20 on one side of the machine and the frame elements 15, 17 and 20 on the opposite side, concentrate strength at about the center of the apparatus where the gearing, indicated generally by the numeral 29, for driving the snapping and husking rolls is located. A very rigid and firm support for this gearing is necessary in order to hold the gears at the ends of the rolls in proper mesh at all times, and the particular construction provided by us effectually accomplishes this result.

Our machine includes a feeding conveyor 30 which is mounted in the top portion of the frame and onto which are delivered the bundles of corn from which the ears of corn are to be removed and stripped of the husks. This feeding table or conveyor is driven by a shaft 31 mounted transversely in the upper part of the machine and actuated by the sprocket gearing 32. A transverse shaft 33 is disposed transversely of the machine below the shaft 31 and constitutes a part of the gearing designated, as an entirety, by the numeral 29. The shaft 33 carries two sprockets at one side of the machine and one of these sprockets engages the chain of the

sprocket gearing 32, while the other sprocket is connected by similar gearing 34 with the shaft 35 arranged near the front end of the machine and equipped with an eccentric 36 whereby a reciprocatory motion is imparted to the pitman 37 which extends rearwardly and is pivotally attached to the side of a shaking screen 38 supported in the lower portion of the machine, the eccentric 36 and pitman 37 being duplicated on the two sides of the machine. Springs 39 cooperate with the eccentrics 36 to maintain the proper engagement of the pitmen with the eccentrics and to secure the desired reciprocation of the shaking screen. Swinging hangers 40 are pivoted at their upper ends to the longitudinal bars 21 and to the bars 12 and 16, respectively, and at their lower ends to the shaking screen so that it will be properly supported for a rocking or oscillatory movement.

A cutter head 41 is provided near the rear end of the machine and this cutter head is operatively connected with the gearing 29 through a chain 29' so that the snapping and husking rolls will rotate in unison with and be driven from the cutter head. The shear plate, indicated at 41', with which the cutter head cooperates, is carried by gusset plates 17', one of which is secured in the angle defined by the frame bars 15 and 17 and the other of which is secured in the angle defined by the corresponding bars 11 and 13. The driving member of gearing 29 is disposed at one side of the machine, as has been stated, and at the other side of the machine the cutter head shaft carries a pulley 42 which is connected by a belt 43 with a pulley 44 on the blower shaft 45. A second pulley 46 is also secured upon the cutter head shaft at the side of the pulley 42 and this pulley 46 receives power from any convenient prime motor, so that necessary movement will be imparted to all the working parts. At one side of the machine the shaft 35 is connected by gearing 47 with the shaft 48 which actuates the ear conveyor 49, so that the husked ears of corn may be carried from the machine and delivered into any desired receptacle.

The ear conveyor belt 49 travels through a trough 50 which is supported at its lower end for rocking movement upon the shaft 48 and is constructed in two sections, hingedly connected, as clearly shown in Fig. 2. The conveyor may thus be folded backwardly so as to extend partly over the machine when the machine is to be shipped or stored, and to support the free end of the conveyor in its folded or collapsed condition, we provide a support consisting of a post 51 which is shown secured upon the top of the machine at the front end thereof and carries a cross bar or plate 52 at its upper end of sufficient width to provide a firm rest for the end of

the conveyor, as shown in Fig. 2. To support the conveyor in its operative position, we provide chains 53 which are engaged around or with the trough in any convenient manner and are also engaged over hooks 54 at the upper ends of supporting arms 55 which are secured to the front end of the machine. These supporting arms 55, as clearly shown in Figs. 1 and 2, have lower branches which are riveted or bolted to the bars 19 and extend outwardly and forwardly therefrom and vertical branches which rise substantially to the top of the machine. Sheet steel plates, indicated at 56, are secured across the front end of the machine immediately above the lower branches of the brackets or arms 55, and these plates not only serve as closures for the end of the machine but also constitute braces to prevent lateral spreading. Similar plates are secured and extend between the upper portions of the rear bars 12 and 16. Immediately above the plates 56, similar plates 57 are hingedly secured at their upper ends to the top of the machine, these swinging plates being normally in their pendent closed positions but being capable of being swung upwardly to permit access to the interior of the machine when repairs or adjustments are needed. A platform 58 rests normally upon the lower horizontal branches of the supporting arms 55, and diagonal braces 55' extending between the same, and is hinged to the plate 56. The operator feeding the corn to the interior of the machine may stand upon this platform 58 and will be in position to guide the bundles onto the feeding conveyor 30, while at the same time he will be at sufficient distance from the snapping and husking rolls to avoid injury. When the ear conveyor is in its lower operative position, it will be clear of the free edge of this platform, but when it is swung upwardly, it will come into contact with the free edge of the platform and will swing the same upwardly, as shown in Fig. 2. To reinforce the platform and guard against collapse of the structure while an operator is standing thereon, we provide the braces 59 which are secured to the front ends of the side bars 9 and extend upwardly and forwardly therefrom to the supporting arms 55 where they are rigidly secured, extending across the bends in the arms and serving as gusset plates to brace the arms and aid in resisting the pulling strain imposed thereon by the ear conveyor. A cross bar 59' is secured to and extends between the upper ends of the arms 55 to prevent lateral spreading thereof and to provide a rest for the operator during the intervals when there are no bundles of corn at hand to be fed into the machine. A small seat may be hung on this cross bar, if desired.

65 The side table or board onto which the bundles are delivered as they fall in passing to the feeding conveyor 30, is shown at 60. It may be arranged at either side of the machine as may be preferred, and it is held in place by having slots which are provided near its inner edge engaged over brackets 62 provided therefor upon the bar 14 or 18, as the case may be, and at the upper ends of the supporting arms 55. It will be noted that this side board is of such extent and so disposed that an operator standing upon the platform 58 can easily reach and handle the bundles which are deposited on the side board. At the same time, the platform 58 may be easily reached by the operator when he is to start work and it is not necessary for him to climb over or under projecting barriers as is the case in most previous machines now known to us. To prevent the bundles being thrown across the machine when it is in operation, a back board 63 is provided and this back board is arranged on edge at the side of the machine remote from the side board 60 so that it constitutes a barrier to the movement of any bundles which may be thrown onto the machine with undue force. The side board 60 and the back board 63 extend up to a hopper or guiding box 64 which extends across the machine immediately over the upper portions of the snapping rolls and serves to guide the bundles of corn to the snapping rolls as well as to prevent an operator or a bystander reaching over the side of the machine and coming into contact with the snapping rolls and incurring serious injury. Bracing rods or props 65 may be provided on the side of the machine to support the outer edge portion of the side board. These props have their lower ends engaged in suitable openings or sockets provided therefor in the frame bars 11 or 21 and in the supporting arms 55, respectively, while their upper ends will be engaged in or against suitable holding members provided on the underside of the side board.

When the machine is to be moved along a road or is to be otherwise transported, the side board is removed from the brackets 62 and is disposed below the side bars 9 of the frame with one end resting upon brackets 66 carried by the rear axle, and its opposite end supported from the side bars by bolts 67. The side board is thus disposed out of the way so that it will not interfere with the travel of the machine over narrow roads or require dismantling of the machine when it is to be secured upon a freight car for shipment.

A blower and blast spout are provided at the rear end of the machine, as indicated at 68 and 69, respectively. The blower shaft is mounted in suitable bearings upon extension bars 70 and 71, the bar 71 being secured to and projecting rearwardly from the rear inclined frame bar 12, while the bar 70 is

disposed laterally beyond the plane of the bar 16 and is connected by a coupling bar 72 with a brace 73 which is secured at its lower end upon the rear axle and extends upwardly and inwardly therefrom to the bar 16 to which it is secured. The bar 70 is further supported by posts 74 secured to and rising from the axle and the rear end of the side bar 9, and a post 75 rises from the side bar 9 at the opposite side of the machine to support the rear end of the bar 71. We thus provide a strong frame support for the blower and its shaft and also so brace the structure as to prevent one side of the frame creeping ahead of the other side and destroying the rigidity of the frame. The blower spout or blast pipe comprises a rigid section 75' which rises directly from the blower 68 and has a turntable 76 at its upper end. This turntable carries the jointed end portions 69 of the spout whereby the spout is carried in a curvilinear manner, either forwardly or laterally or rearwardly, the said jointed portions 69 being connected with a rigid pipe section 77 of the usual length and provided at its end with a collar or band 78 having a flange 79 and equipped with an eye 80. A second straight section 81 is likewise provided with a band 82 having a flange 83. When the machine is in use, the flanges 79 and 83 are bolted together so as to form a tight joint with the sections in alinement so that the chaff and other waste matter may be delivered at a point distant from the machine. The section 81 is provided at its delivery end with a deflecting hood 84 whereby the chaff and other material flowing through the spout will be directed downwardly to the ground. The spout and blower are, of course, located at one side of the machine, and to prevent warping of the machine through the vibration of the parts in operation, we provide a diagonal brace 85 which is secured at one end to the rear frame bar 12 and at its opposite end to the turntable 76. At the same side of the machine as the blower and the spout, a brace 86 is provided which extends from the bar 16 to the turntable and may be an extension of the upper beam 18.

To support the blast spout, we provide a prop consisting of a straight shank 87 which may be secured to brackets bolted to the frame bar 19, or to an arm 55, and has its upper end turned laterally, as shown at 88, a stirrup or rest 89 being secured upon and carried by the free end of the said laterally turned portion. This stirrup 89 is adapted to fit partly around the section 77 of the spout when the spout is arranged to project forwardly over the machine, as shown in Figs. 2 and 3, in which case it will be noted that the sections are separated and are tied side by side with a rope 90. It will be seen that in this described and illustrated

position of the prop, the lateral arm 88 projects rearwardly over the machine and the spout is arranged in disassembled, compact form, so that the machine may be driven over a road or may be transported, while 70 economizing space. If it be desired to move the machine over a road without disconnecting the sections of the spout or blast pipe, the prop 87 is turned so that the arm 88 will project forwardly and the stirrup will then 75 be properly located to engage under the outer section of the pipe and support the same.

To support the spout in its working position, we provide a mast 91 which has its 80 lower end adapted to rest upon a base block 92 secured rigidly upon the rear bar 16, and it is held in position to rotate about its own axis upon the said base block by a staple or ring 93 which is fixed upon the 85 side of the brace 86. The mast is provided intermediate its ends with a lateral bend or offset portion 94 adapted to fit around the spout when the spout is projecting over the machine. At the upper end of the mast a hook 95 is pivotally mounted to carry the pulley block 96 over which the hoisting cable 97 runs, and the base block 92 and the ring 93 are so disposed that the upper end of the mast will be brought into the vertical plane 95 of the turntable 76 and alined therewith, the hook 95 being thus permitted to turn with the spout without causing entanglement of the hoisting cable. The end of the cable 97 is secured to a windlass or winding shaft 98 mounted upon the mast in the usual manner. This mast, when the machine is to be transported, is secured against one of the side bars 9 as shown in Fig. 2, so that it will be out of the way and yet will not be apt to be lost. The mast may be easily mounted when the machine is to be set up for use by a single operator, inasmuch as all that needs to be done is to engage the mast upon the base block and fit the ring or other retaining member 93 in place. The cable 97 carries a block and hook which is then engaged with the eye 80 upon the spout, after which a slight winding of the cable will lift the spout out of the stirrup 89 and permit it to be swung to the operating position.

Upon the blower shaft, we secure a spiral feeder 100 which leads into the blower and overcomes the choking which would otherwise be caused by the blower shaft extending across the path of the outgoing material.

Having thus described the invention, what is claimed as new is:

1. A corn-husking machine comprising a frame, husking rolls mounted in the frame, a feeding conveyor mounted in the top of the frame, a side board detachably mounted upon the side of the frame adjacent said feeding conveyor and constituting a receiving table, a back board detachably mounted 125

at the opposite side of the frame and constituting a bundle stop, supporting arms secured to the front end of the frame and projecting forwardly therefrom and then upwardly at the side of the front end of the side board, and a platform resting upon the forwardly projecting portions of said arms.

5 2. In a corn-husking machine, the combination of front and rear wheels, axles carrying said wheels, a frame supported by said axles, a side table, means for detachably supporting said table on the side of the frame at the top thereof, brackets projecting from the rear axle to support the rear end of the 10 side table for transportation, and means at the bottom of the frame to support the front end of the side table.

15 3. A corn-husking machine including means for stripping husks from ears of corn, a blower for driving off waste, a blower shaft mounted transversely in the rear end of the machine, and a spiral feeder on the blower shaft at one side of and leading axially into the blower.

20 4. A corn-husking machine comprising upper and lower side bars, traveling supports for the side bars, longitudinally disposed upwardly converging bars rising from the lower side bars, the forward bars being secured at their rear ends to the corresponding rear bars and the rear bars being secured to the upper side bars, intermediate bars rising from the lower side bars and connected with the upper side bars and the 25 converging bars, vertical bars rising from the front ends of the lower side bars and connected to the upper side bars. panels

30 secured to the several bars whereby to constitute a housing enclosing all the working parts, husking rollers carried by the forward portions of the forward converging bars, snapping rollers carried by the upper portions of the intermediate bars, and frame plates secured to the upper ends of the intermediate bars and the rear converging 35 bars and constituting guards for the upper ends of the snapping rollers.

5. A corn-husking machine comprising a frame, husking rollers mounted in the frame, a feeding conveyer mounted in the top of the frame, a side table detachably mounted upon one side of the frame adjacent the feeding conveyer, and a back board detachably mounted at the opposite side of the 40 frame and constituting a bundle stop.

50 6. In a corn-husking machine, the combination of a main supporting frame, snapping rolls supported by said frame in a steeply inclined position, a cutter mounted in the frame below and near the snapping rolls, husking rolls mounted on the frame below the snapping rolls in a relatively slightly inclined position, unitary gearing common to and operatively connecting the lower ends of the snapping rolls and the upper ends of the husking rolls, means for rotating the cutter, and means for transferring rotation from the cutter directly to the gearing connecting the snapping and 55 the husking rolls.

60 In testimony whereof we affix our signatures.

THEODORE H. OPPENHEIM. [L. S.]
BERNARD SELHORST. [L. S.]
